UNITED STATES PATENT OFFICE.

WILLIAM ELLARD, OF WOBURN, MASSACHUSETTS.

MACHINE FOR FINISHING LEATHER.

Specification of Letters Patent No. 31,879, dated April 2, 1861.

To all whom it may concern:

Be it known that I, WILLIAM ELLARD, of Woburn, in the county of Middlesex and State of Massachusetts, have invented a new and useful Improvement in Machinery for Glossing or Finishing Leather, and do hereby declare the same to be fully described in the following specification and represented in the accompanying drawings, of 10 which—

Figure 1, is a front view; Fig. 2, a side elevation, and Fig. 3, a transverse section of a machine containing my invention.

The nature of the said invention consists 15 in a new combination and arrangement of devices for effecting the proper reciprocating movements of the glossing or finishing tool relatively to a straight bed for supporting the leather.

20 In the drawings, A denotes the table or frame of the machine—while B is the bed on which the leather to be glossed is to be laid. This bed has a straight or nearly straight upper surface and is supported by 25 means of rods, *a a*, resting on springs, *b b*. Over this bed is the glossing, dicing or finishing tool C, whose carrier or holder D, is hinged or jointed to the lower extremity of the cross bar *e*, of a T lever, E, which is 30 composed of two bars *d e*, fastened together and arranged with respect to one another as shown in the drawings. An abutment or stop plate *f*, is fixed to the lower part of the bar *e* and serves to support the tool holder while the tool is being drawn over 35 the bed. The rear end of the bar *d* is connected to a cranked wheel G by a pin or stud *g*, the said cranked wheel being fixed on a driving shaft H.

40 The upper part of the bar *e*, is slotted or forked to receive a friction roller, I, which not only runs on a pin *h*, passed through the said bar *e*, but rests on a bent rail K, and bears against a cam L, which is affixed to 45 the lower side of an arm M, projecting from the frame A, and over the bed B, as shown in the drawings. The bar or rail K, is formed and extended from the arm M, as shown in the drawings. Its object is to prevent 50 the glossing tool from dropping into contact with the bed (or any piece of leather

that may be thereon) while the T lever may be in the act of being forced backward. During each entire revolution of the driving shaft in the direction exhibited by the arrow *k*, the T lever will not only be driven forward but be forced backward over the bed. While the T bar is being driven forward, the crank pin *g*, should be running through the upper half circle of its revolution, in which case the glossing tool, in consequence of the peculiar co-operation and action of the T lever, its crank and the cam L, will be moved along in contact with the bed or the leather when on the latter. But while the crank pin may be going through its lower semi-circle of revolution, the glossing tool will not only be forced backward, but be lifted and maintained off the bed (or its leather) and so as to enable the leather to be moved on the bed in order that the tool during its next forward movement may be caused to work on a fresh portion of the surface of the leather and either polish, grain or dice it as circumstances may require.

Although the mechanism above described for operating the glossing tool, resembles in some respects, others in use for a like purpose, yet it differs materially therefrom and for simplicity of construction and operation presents comparatively speaking important advantages.

I lay no claim to the combination of a vibratory slicker bar, a plane surface bed and machinery for rotating the bar and elevating the slicker or polisher off the leather or its bed during every retrograde movement of the slicker.

What I claim as my invention or improvement is—

The above specified arrangement and application of the bars, *d e*, (or the T lever E,) the cam L, the roller I and the retainer or rail K, with respect to each other and the glossing tool carrier D, the bed B, and the crank wheel G, the whole being to operate substantially as specified.

WILLIAM ELLARD.
